(57) **ABSTRACT**

A coil device includes a winding core, a wire, and a terminal fitting. The winding core is made of a magnetic material and includes a flange. The wire is wound around the winding core. The terminal fitting is attached to a part of an outer surface of the flange. The terminal fitting includes a contact part and a protrusion plate part. The contact part is contacted with the outer surface of the flange. The protrusion plate part is formed integrally with the contact part and protrudes away from the flange. The protrusion plate part includes a wire connection surface and a main mounting surface. A lead end of the wire is connected to the wire connection surface. The main mounting surface is located opposite to the wire connection surface and is connectable to an external circuit.

COIL DEVICE

BACKGROUND OF THE INVENTION

The present invention relates to a winding-type coil device.

As a winding-type coil device, for example, a coil device shown in Patent Document 1 is known. In the conventional winding-type coil device of Patent Document 1, metal terminals are attached to flanges of a magnetic core using adhesive or so, and an end of a wire constituting a coil is connected at a location dented from a mounting surface of the metal terminal.

When such a coil device with a conventional structure is used for power supply applications, however, the mounting surface of the metal terminal and a connection part of the wire end are away from each other. Thus, there is a problem with increase in DC resistance.

Patent Document 1: JP2018056399 (A)

BRIEF SUMMARY OF INVENTION

The present invention has been achieved under such circumstances. It is an object of the invention to provide a coil device having a low DC resistance and being capable of also being used for power supply applications.

To achieve the above object, a coil device according to the present invention includes:

a winding core made of a magnetic material and including a flange;
a wire wound around the winding core; and
a terminal fitting attached to a part of an outer surface of the flange,
wherein
the terminal fitting includes:
a contact part contacted with the outer surface of the flange; and
a protrusion plate part formed integrally with the contact part and protruding away from the flange, and
the protrusion plate part includes:
a wire connection surface to which a lead end of the wire is connected; and
a main mounting surface located opposite to the wire connection surface and being connectable to an external circuit.

In the coil device according to the present invention, the main mounting surface connected to an external circuit and the wire connection surface for the lead end of the wire are mutually located on the other side of the protrusion plate part. Thus, the wire connection surface and the main mounting surface are substantially close to each other only with the thickness of the protrusion plate part, and it is possible to extremely reduce a DC resistance of the terminal fitting from the connection part of the lead end of the wire to an external circuit board and is also possible to extremely reduce a DC resistance of the coil device as a whole. Thus, the coil device according to the present invention can favorably be used for power supply applications.

Even when the coil device according to the present invention is used for signal system applications, the increase in insertion loss (IL) can be restrained, and the coil device according to the present invention can also favorably be used for signal system applications.

Preferably, the protrusion plate part includes a base part continuing to the contact part and protruding from the flange and a tip bending part bending in turn back manner at a tip

2

of the base part, and a lead end of the wire is sandwiched between the tip bending part and the base part.

When the lead end of the wire is sandwiched between the tip bending part and the base part, the lead end is easily connected to the terminal fitting.

The wire connection surface or the main mounting surface may be formed on a front surface or a rear surface of the tip bending part. Instead, the wire connection surface or the main mounting surface is formed on a front surface or a rear surface of the base part corresponding to the tip bending part. Instead, the protrusion plate part may not include the tip bending part.

Preferably, a sub-mounting surface being flush with the main mounting surface or located on an inner side of the main mounting surface is formed on a part of an outer surface of the contact part. This structure improves the mounting strength of the coil device and makes it easy to stably mount the coil device on a circuit board or so.

Preferably, a gap distance between the protrusion plate part and the flange in a perpendicular direction to the main mounting surface is twice or larger than a thickness of the protrusion plate part at a location where the lead end of the wire is connected to the protrusion plate part. In this structure, for example, the lead end of the wire can easily be connected to the protrusion plate part by laser welding or so. In addition, a thermal deformation stress of a circuit board or so is hard to travel to the flange, and the connection strength of the coil device to the circuit board is improved.

A plate-like member may be bonded on the outer surface of the flange located opposite to the main mounting surface. The plate-like member may be a magnetic member or a nonmagnetic member. In addition, the plate-like member may be a member formed by application of resin. Preferably, such plate-like members have a flat surface. A suction member for pickup can detachably be attached to the flat surface. This improves the handling performance.

BRIEF DESCRIPTION OF DRAWINGS

FIG. 1A is a perspective view of a coil device according to an embodiment of the present invention;

FIG. 1B is a lateral view of the coil device shown in FIG. 1A;

FIG. 1C is a front view of the coil device shown in FIG. 1A;

FIG. 1D is a bottom view of the coil device shown in FIG. 1A;

FIG. 2 is a perspective view of a drum-type core of the coil device shown in FIG. 1A;

FIG. 3 is a perspective view of a terminal metal fitting of the coil device shown in FIG. 1A;

FIG. 4A is a perspective view of a coil device according to another embodiment of the present invention;

FIG. 4B is a perspective view of a coil device according to a modified example of FIG. 4A;

FIG. 5 is a perspective view of a terminal metal fitting of the coil device shown in FIG. 4A;

FIG. 6A is a perspective view of a terminal bracket used for a coil device according to further another embodiment of the present invention;

FIG. 6B is a perspective view of a terminal metal fitting used for a coil device according to further another embodiment of the present invention; and

FIG. 6C is a perspective view of a terminal metal fitting used for a coil device according to further another embodiment of the present invention.

DETAILED DESCRIPTION OF INVENTION

Hereinafter, the present invention is explained based on the embodiments shown in the figures.

First Embodiment

A coil device **10** according to an embodiment of the present invention shown in FIG. 1A is used for any purposes and is used as, for example, a winding-type common mode filter. The coil device **10** can also be used as a balun, a dual inductor, etc.

The coil device **10** includes a drum core **20**, a coil unit **40** wound around a winding core **22** of the drum core **20**, and a flat plate-like member **30** disposed on the drum core **20**. In the explanation of the coil device **10**, the X-axis direction is a direction parallel to a main mounting surface for the coil device **10** and to the winding axis of the winding core **22** of the drum core **20**, the Y-axis direction is a direction parallel to the main mounting surface as similarly to the X-axis and perpendicular to the X-axis, and the Z-axis is a normal direction of the main mounting surface.

As shown in FIG. 2, the drum core **20** includes the winding core **22** having a bar shape extending in the X-axis direction and a first flange **24** and a second flange **26** as a pair of core ends arranged on both ends of the winding core **22**. The first flange **24** and the second flange **26** have substantially the same shape and are arranged in the winding core **22** so as to substantially be parallel to each other with a predetermined space in the X-axis direction.

The winding core **22** is connected to a substantially central area of each of surfaces of the pair of flanges **24** and **26** facing each other and is integrated with the pair of flanges **24** and **26**. In the present embodiment, the winding core **22** has a rectangular cross-sectional shape, but may have any cross-sectional shape, such as circular.

Preferably, a plate-like member **30** shown in FIG. 1A is attached to an upper end of the drum core **20** in the Z-axis direction. Preferably, the plate-like member **30** is attached to an anti-mounting-side core surface **24b** of the first flange **24** and an anti-mounting-side core surface **26b** of the second flange **26** so as to bridge these anti-mounting-side core surfaces.

In the present embodiment, as shown in FIG. 2, the first flange **24** is structured by a rectangular parallelepiped as a whole, and rectangular notches **24c3** are formed at the lower ends of the rectangular parallelepiped shape on both sides in the Y-axis direction. The first flange **24** includes a mounting-side core surface **24a** (lower surface in the Z-axis direction), the anti-mounting-side core surface **24b** located opposite to the mounting-side core surface **24a**, an outer end surface **24c** in the X-axis direction, an inner surface **24d** facing the winding core **22**, and a pair of lateral surfaces **24e** and **24e** located opposite to each other in the Y-axis direction.

Terminal attachment surfaces **24c1** dented inward in the X-axis direction (toward the center of the core **20**) from the outer end surface **24c** are formed at the lower parts of the outer end surface **24c** on both sides in the Y-axis direction. A terminal insulation projection **24c2** is formed between the terminal attachment surfaces **24c1** in the Y-axis direction and insulates a first terminal (terminal fitting) **51** and a second terminal (terminal fitting) **52** attached as shown in FIG. 1A. An inner surface of an outer-end-surface contact portion **51a1** of a terminal body **51a** of the first terminal **51** and an inner surface of an outer-end-surface contact portion **52a1** of a terminal body **52a** of the second terminal **52**

shown in FIG. 3 are attached (or bonded as necessary) on the terminal attachment surfaces **24c1** shown in FIG. 2.

The step depth of the terminal attachment surfaces **24c1** dented from the outer end surface **24c** shown in FIG. 2 toward the inner side in the X-axis direction is preferably as large as a plate thickness of the first terminal **51** or the second terminal **52** shown in FIG. 3, but may be smaller or larger than the plate thickness. The shape of the first terminal **51** and the shape of the second terminal **52** shown in FIG. 3 are line-symmetric to each other.

The first terminal **51** is structured by a conductive terminal plate or so and includes the terminal body **51a** and a protrusion plate part **51b** formed by bending a sheet of conductive plate-like member of a metal plate or so. The terminal body **51a** includes the outer-end-surface contact portion **51a1** with a substantially L shape attached to one terminal attachment surface **24c1** formed on the outer end surface **24c** of the flange **24** shown in FIG. 2 using adhesive or so. In addition, the terminal body **51a** includes a mounting-side contact portion **51a2** with a rectangular plate shape formed by bending from the lower end of the outer-end-surface contact portion **51a1** in the Z-axis direction to the X-axis direction.

The outer-end-surface contact portion **51a1** of the terminal body **51a** shown in FIG. 3 is fixed to the terminal attachment surface **24c1** of the flange **24** shown in FIG. 2 using adhesive or so. The mounting-side contact portion **51a2** shown in FIG. 3 is contacted with the mounting-side core surface **24a** shown in FIG. 2 with a predetermined space (or no space). The outer surface of the mounting-side contact portion **51a2** located opposite to the surface contacted with the mounting-side core surface **24a** shown in FIG. 2 is a sub-mounting surface **51a3**. The role of the sub-mounting surface **51a3** is mentioned below.

The protrusion plate part **51b** shown in FIG. 3 and protruding outward in the Y-axis direction from the mounting-side core surface **24a** of the flange **24** at the lower end of the flange **24** shown in FIG. 2 is formed integrally with the mounting-side contact portion **51a2** of the terminal body **51a** shown in FIG. 3. The protrusion plate part **51b** includes a base part **51c** being flush with the mounting-side contact portion **51a2** of the terminal body **51a** and extending outward in the Y-axis direction and a tip bending part **51d** bending in turn back manner from the tip of the base part **51c**.

In the present embodiment, the tip bending part **51d** bends upward in the Z-axis direction and turns back at the tip of the base part **51c**, the outer surface of the base part **51c** located opposite to the tip bending part **51d** is a main mounting surface **51c1**, and the inner surface of the base part **51c**, which the tip bending part **51d** is located, is a connection surface (wire connection surface) **51c2**. As shown in FIG. 1C, a lead end **41a** (one lead end) of a first wire **41** (one wire) constituting the coil unit **40** shown in FIG. 1B is sandwiched and caulked by the connection surface **51c2** of the base part **51c** and the tip bending part **51d**. After the caulking, the terminal **51** and the lead end **41a** of the wire **41** may be connected by soldering, laser welding, etc.

In the present embodiment, as shown in FIG. 1C, the main mounting surface **51c1** and the sub-mounting surface **51a3** of the first terminal **51** are outer surfaces being flush with each other, and the main mounting surface **51c1** is mainly connected to a circuit pattern of an external circuit board (not shown), but the sub-mounting surface **51a3** may also be connected to the circuit pattern at the same time. The connection to the circuit pattern of the external circuit board is carried out in any manner, such as solder connection.

As with the first terminal 51, the second terminal 52 is structured by a conductive terminal plate or so and includes a terminal body 52a and a protrusion plate part 52b formed by bending a sheet of conductive plate-like member of a metal plate or so. The terminal body 52a includes the outer-end-surface contact portion 52a1 with a substantially L shape attached to the other terminal attachment surface 24c1 formed on the outer end surface 24c of the flange 24 shown in FIG. 2 using adhesive or so. In addition, the terminal body 52a includes a mounting-side contact portion 52a2 with a rectangular plate shape formed by bending from the lower end of the outer-end-surface contact portion 52a1 in the Z-axis direction to the X-axis direction.

The outer-end-surface contact portion 52a1 of the terminal body 52a shown in FIG. 3 is fixed to the terminal attachment surface 24c1 of the flange 24 shown in FIG. 2 using adhesive or so. The mounting-side contact portion 52a2 shown in FIG. 3 is contacted with the mounting-side core surface 24a shown in FIG. 2 with a predetermined space (or no space). The outer surface of the mounting-side contact portion 52a2 located opposite to the surface contacted with the mounting-side core surface 24a shown in FIG. 2 is a sub-mounting surface 52a3. The role of the sub-mounting surface 52a3 is similar to that of the sub-mounting surface 51a3.

The protrusion plate part 52b shown in FIG. 3 and protruding outward in the Y-axis direction from the mounting-side core surface 24a of the flange 24 at the lower end of the flange 24 shown in FIG. 2 is formed integrally with the mounting-side contact portion 52a2 of the terminal body 52a shown in FIG. 3. The protrusion plate part 52b includes a base part 52c being flush with the mounting-side contact portion 52a2 of the terminal body 52a and extending outward in the Y-axis direction and a tip bending part 52d bending in turn back manner from the tip of the base part 52c.

In the present embodiment, the tip bending part 52d bends upward in the Z-axis direction and turns back at the tip of the base part 52c, the outer surface of the base part 52c located opposite to the tip bending part 52d is a main mounting surface 52c1, and the inner surface of the base part 52c, which the tip bending part 52d is located, is a connection surface (wire connection surface) 52c2. As shown in FIG. 1C, a lead end 42a (one lead end) of a second wire 42 (the other wire) constituting the coil unit 40 shown in FIG. 1B is sandwiched and caulked by the connection surface 52c2 of the base part 52c and the tip bending part 52d. After the caulking, the terminal 52 and the lead end 42a of the wire 42 may be connected by soldering, laser welding, etc.

In the present embodiment, as shown in FIG. 1C, the main mounting surface 52c1 and the sub-mounting surface 52a3 of the second terminal 52 are outer surfaces being flush with each other, and the main mounting surface 52c1 is mainly connected to a circuit pattern of an external circuit board (not shown), but the sub-mounting surface 52a3 may also be connected to the circuit pattern at the same time. The connection to the circuit pattern of the external circuit board is carried out in any manner, such as solder connection.

In the present embodiment, the second flange 26 has a similar structure to the first flange 24, but may not necessarily have the same structure. In the present embodiment, as shown in FIG. 2, the second flange 26 is structured by a rectangular parallelepiped as a whole, and rectangular notches 26c3 are formed at the lower ends of the rectangular parallelepiped on both sides in the Y-axis direction. The second flange 26 includes a mounting-side core surface 26a (lower surface in the Z-axis direction), the anti-mounting-

side core surface 26b located opposite to the mounting-side core surface 26a, an outer end surface 26c in the X-axis direction, an inner surface 26d facing the winding core 22, and a pair of lateral surfaces 26e and 26e mutually located on the other side in the Y-axis direction.

Terminal attachment surfaces 26c1 dented inward in the X-axis direction (toward the center of the core 20) from the outer end surface 26c are formed on lower parts of the outer end surface 26c on both sides in the Y-axis direction. A terminal insulation projection (not shown; corresponding with the terminal insulation projection 24c2) is formed between the terminal attachment surfaces 26c1 in the Y-axis direction and insulates the first terminal 51 and the second terminal 52 on the back in the X-axis direction shown in FIG. 3. An inner surface of an outer-end-surface contact portion 51a1 of a terminal body 51a of the first terminal 51 and an inner surface of an outer-end-surface contact portion 52a1 of a terminal body 52a of the second terminal 52 shown in FIG. 3 are attached (or bonded as necessary) on the terminal attachment surfaces 26c1 shown in FIG. 2.

The attachment structure of the first terminal 51 and the second terminal 52 on the back in the X-axis direction shown in FIG. 3 to the second flange 26 shown in FIG. 2 is similar to that to the first flange 24 shown in FIG. 2 mentioned above and is thereby not explained in detail.

As shown in FIG. 1C, the lead end 41a (one leading portion) of the first wire 41 is connected to the connection surface 51c2 of the first terminal 51, and the lead end 42a (one leading portion) of the second wire 42 is connected to the connection surface 52c2 of the second terminal 52. Moreover, the lead end 41b (the other leading portion) of the first wire 41 is connected to the connection surface 52c2 of the second terminal 52 on the back in the X-axis direction shown in FIG. 3, and the lead end 42b (the other leading portion) of the second wire 42 shown in FIG. 1C is connected to the connection surface 51c2 of the first terminal 51 on the back in the X-axis direction shown in FIG. 3. These are connected by any method, such as welding, resistance welding, ultrasonic welding, caulking, thermocompression bonding, and heat welding (preferably, laser welding, soldering, etc.).

As shown in FIG. 1A, FIG. 1B, and FIG. 1D, the coil unit 40 is formed around the winding core 22 of the drum core 20. In the present embodiment, the coil unit 40 is structured by two wires 41 and 42. The wires 41 and 42 are structured by, for example, a coated wire formed by covering a core made of a good conductor (e.g., copper wire) with an insulating coverage film and are wound around the winding core 22, for example, in a double-layer structure. In the present embodiment, the cross-sectional areas of conductive parts of the wires 41 and 42 are the same as each other.

In the present embodiment, the first wire 41 and the second wire 42 are wound around the winding core 22 by a normal bifilar winding, but a cross part may be formed at a predetermined location in the winding axis of the winding core 22.

In the manufacture of the coil device 10, two pairs of terminals 51 and 52 shown in FIG. 3 are initially attached to the drum core 20 shown in FIG. 2. Preferably, only the inner surfaces of the outer-end-surface contact portions 51a1 and 52a1 of the terminals 51 and 52 are bonded with the terminal attachment surfaces 24c1 or 26c1. Preferably, the mounting-side contact portions 51a2 and 52a2 of the terminals 51 and 52 are not bonded with the mounting-side core surface 24a (26a) of the flange 24 (26). This is because a vibration of an

external circuit board not shown is prevented from directly traveling to the mounting-side core surface $24a$ ($26a$) of the flange 24 (26).

Prepared are the drum-type drum core 20 with the terminals 51 and 52 manufactured in such a manner, the flat plate-like member 30 , and the wires 41 and 42 . The drum core 20 is made of magnetic material and can be manufactured by, for example, pressing and sintering a magnetic material with a comparatively high permeability (e.g., Ni—Zn based ferrite, Mn—Zn based ferrite) or a magnetic powder composed of metal magnetic material or so. The flat plate-like member 30 is preferably made of the same or different magnetic material from the drum core 20 , but is not necessarily made of magnetic material.

The terminals 51 and 52 are structured by a metal terminal made of phosphor bronze, tough pitch steel, pure copper, brass, silver, gold, metallic alloys with solder bondability, etc. Each of the terminals 51 and 52 has any thickness, but preferably has a thickness of 50-300 μm .

For example, the wires 41 and 42 can be formed by covering a core made of a good conductor of copper (Cu) or so with an insulating material made of imide-modified polyurethane or so and further covering the outermost surface with a thin resin film of polyester or so. The drum core 20 on which the terminals 51 and 52 are installed and the wires 41 and 42 are set to a winding machine, and the wires 41 and 42 are wound around the winding core 22 of the drum core 20 in a predetermined order. Each of the wires 41 and 42 has any diameter, but preferably has a diameter of 10-300 μm .

In the present embodiment, the first wire 41 and the second wire 42 are wound by bifilar winding. The lead ends $41a$, $42a$, $41b$, and $42b$ of the lead portions (wire ends) of the wound wires 41 and 42 are connected after the tip bending part $51d$ or $52d$ is caulked to the connection surface $51c2$ or $52c2$ of the predetermined terminals 51 and 52 shown in FIG. 3.

After the winding operation of the wires 41 and 42 to the winding core 22 , the flat plate-like member 30 is connected to the anti-mounting-side core surfaces $24b$ and $26b$ of the flanges 24 and 26 by any method, such as adhesion.

In the coil device 10 according to the present embodiment, the wire length of the lead end $41a$ (one lead portion) of the first wire 41 from the coil unit 40 to the connection surface $51c2$ of the first terminal 51 and the wire length of the lead end $42a$ (one lead portion) of the second wire 42 from the coil unit 40 to the connection surface $52c2$ of the second terminal 52 are preferably substantially the same, but may be different from each other. Preferably, the winding number of the first wire 41 and the winding number of the second wire 42 in the coil unit 40 are the same as each other. This structure further improves mode conversion characteristics.

In the coil device 10 according to the present embodiment, as shown in FIG. 1C, the main mounting surface $51c1$ ($52c1$) of the terminal 51 (52) and the connection surface $51c2$ ($52c2$), which is a wire connection surface for the lead end $41a$ ($42a$) of the wire 41 (42), are mutually located on the other side of the base part $51c$ ($52c$). Thus, the connection surface $51c2$ ($52c2$) and the main mounting surface $51c1$ ($52c1$) are substantially close to each other only with the thickness of the base part $51c$ ($52c$) of the protrusion plate part $51b$ ($52b$), and it is possible to extremely reduce a DC resistance of the terminal 51 (52) from the connection part of the lead end $41a$ ($42a$) of the wire 41 (42) to an

external circuit board (not shown). Thus, it is also possible to extremely reduce a DC resistance of the coil device 10 as a whole.

As a result, the coil device 10 according to the present embodiment can also favorably be used for power supply applications. Even when the coil device 10 according to the present embodiment is used for signal system applications, the increase in insertion loss (IL) can be restrained, and the coil device 10 according to the present embodiment can also favorably be used for a high frequency signal system application of, for example, 100 MHz or more.

In the present embodiment, the contact part of the terminal 51 (52) made of metal plate is partly contacted with a part of the flange 24 (26) of the drum core 20 (excluding the mounting-side core surface $24a$ ($26a$)), and a vibration, a thermal deformation force, or the like from an external circuit board is thereby hard to directly travel to the drum core. As a result, the connection strength of the coil device 10 to an external circuit board is improved.

In the present embodiment, as shown in FIG. 3, the protrusion plate part $51b$ ($52b$) includes the base part $51c$ ($52c$) shown in FIG. 3 continuing to the mounting-side contact portion $51a2$ ($52a2$) of the terminal body $51a$ ($52a$) and protruding from the flange 24 (26) shown in FIG. 2. As shown in FIG. 3, the protrusion plate part $51b$ ($52b$) includes the tip bending part $51d$ ($52d$) bending in turn back manner at the tip side of the protrusion plate part $51b$ ($52b$). Then, as shown in FIG. 1C, the lead end $41a$ ($42a$) ($41b$, $42b$) of the wire 41 (42) is sandwiched and caulked between the base part $51c$ ($52c$) and the tip bending part $51d$ ($52d$). When the lead end $41a$ ($42a$) ($41b$, $42b$) of the wire 41 (42) is sandwiched between the base part $51c$ ($52c$) and the tip bending part $51d$ ($52d$) in such a manner, the lead end $41a$ ($42a$) is easily connected to the terminal 51 (52).

In the present embodiment, the sub-mounting surface $51a3$ ($52a3$) being flush with the main mounting surface $51c1$ ($52c2$) or located on the inner side of the main mounting surface $51c1$ ($52c2$) is formed on the outer surface of the mounting-side contact portion $51a2$ ($52a2$) of the terminal 51 (52). This structure improves the mounting strength of the coil device 10 and makes it easy to stably mount the coil device 10 on a circuit board (not shown) or so.

In the present embodiment, as shown in FIG. 1C, a gap distance $Z1$ between the tip bending part $51d$ ($52d$) of the protrusion plate part $51b$ ($52b$) and the flange 24 (26) at a connection location of the lead end $41a$ ($42a$) of the wire 41 (42) in the Z-axis direction perpendicular to the main mounting surface $51c1$ ($52c2$) is twice or larger than a thickness of the protrusion plate part $51b$ ($52b$). In this structure, for example, the lead end $41a$ ($42a$) of the wire 41 (42) can easily be connected to the protrusion plate part $51b$ ($52b$) by laser welding, soldering, or the like. In addition, a thermal deformation stress of a circuit board (not shown) or so is hard to travel to the flanges, and the connection strength of the coil device 10 to the circuit board is improved.

In the present embodiment, as shown in FIG. 1A, the coil device 10 according to the present embodiment further includes the flat plate-like member 30 bridging the anti-mounting-side core surface $24b$ of the first flange 24 and the anti-mounting-side core surface $26b$ of the second flange 26 . When the flat plate-like member 30 is made of magnetic material, a closed magnetic circuit can be formed by combination with the drum core 20 made of magnetic material, and magnetic characteristics of the coil device 10 are improved.

Incidentally, the plate-like member 30 may be a nonmagnetic member. In addition, the plate-like member 30 may be a member formed by application of resin. Preferably, such plate-like members 30 have a flat surface. A suction member for pickup can detachably be attached to the flat surface. This improves the handling performance.

Second Embodiment

A coil device according to Second Embodiment of the present invention is different from the coil device 10 according to First Embodiment only in the following structure and demonstrates effects similar to those of First Embodiment. The overlapping matters with First Embodiment are not explained. In the figures, common components with First Embodiment are given common references.

In a coil device 110 according to the present embodiment, as shown in FIG. 4A and FIG. 5, the first terminal 51 and the second terminal 52 of the coil device 10 according to First Embodiment shown in FIG. 1A to FIG. 3 are respectively replaced with a first terminal 151 and a second terminal 152.

The first terminal 151 shown in FIG. 5 is structured by a conductive terminal plate or so and includes a terminal body 151a and a protrusion plate part 151b formed by bending a sheet of conductive plate-like member of a metal plate or so. The terminal body 151a includes an outer-end-surface contact portion 151a1 attached to one terminal attachment surface 24c1 formed on the outer end surface 24c of the flange 24 shown in FIG. 2 using adhesive or so. In addition, the terminal body 151a includes a mounting-side contact portion 151a2 with a rectangular plate shape formed by bending from the lower end of the outer-end-surface contact portion 151a1 in the Z-axis direction to the X-axis direction.

The outer-end-surface contact portion 151a1 of the terminal body 151a shown in FIG. 5 is fixed to the terminal attachment surface 24c1 of the flange 24 shown in FIG. 2 using adhesive or so. The mounting-side contact portion 151a2 shown in FIG. 5 is contacted with the mounting-side core surface 24a shown in FIG. 2 with a predetermined space (or no space). The outer surface of the mounting-side contact portion 151a2 located opposite to the surface contacted with the mounting-side core surface 24a shown in FIG. 2 is a sub-mounting surface 151a3. The role of the sub-mounting surface 151a3 is mentioned below.

A lateral contact portion 151a4 contacted with a lower part of the lateral surface 24e of the flange 24 shown in FIG. 2 (see FIG. 5) is formed integrally with an outer end of the outer-end-surface contact portion 151a1 of the terminal body 151a in the Y-axis direction shown in FIG. 5. As shown in FIG. 5, the protrusion plate part 151b protruding downward in the Z-axis direction from the lateral surface 24e of the flange 24 shown in FIG. 2 is formed integrally with the terminal body 151a at a lower part of the lateral contact portion 151a4 in the Z-axis direction.

The protrusion plate part 151b includes a first base part 151e being flush with the lateral contact portion 151a4 of the terminal body 151a and extending downward in the Z-axis direction, a second base part 151c formed integrally and bending inward in the Y-axis direction from the lower end of the first base part 151e in the Z-axis direction, and a tip bending part 151d bending in turn back manner from the tip of the second base part 151c.

In the present embodiment, the tip bending part 151d bends outward in the Y-axis direction and turns back at the tip of the second base part 151c, the outer surface of the second base part 151c located opposite to the tip bending part 151d is a main mounting surface 151c1, and the inner

surface of the second base part 151c, where the tip bending part 151d is located, is a connection surface (wire connection surface) 151c2. As shown in FIG. 4A, a lead end 41a (one lead end) of the first wire 41 (one wire) constituting the coil unit 40 is sandwiched and caulked by the connection surface 151c2 of the second base part 151c and the tip bending part 151d. After the caulking, the terminal 151 and the lead end 41a of the wire 41 may be connected by soldering, laser welding, etc.

In the present embodiment, the main mounting surface 151c1 of the first terminal 151 protrudes downward in the Z-axis direction from the sub-mounting surface 151a3 by a predetermined distance Z2. Preferably, the predetermined distance Z2 is larger than zero and is about four times or less (more preferably, twice or less) of the thickness of the plate-like member constituting the first terminal 151. In the present embodiment, the main mounting surface 151c1 is mainly connected to a circuit pattern of an external circuit board (not shown), but the sub-mounting surface 151a3 may also be connected to the circuit pattern at the same time. The connection to the circuit pattern of the external circuit board is carried out in any manner, such as solder connection.

As with the first terminal 151, the second terminal 152 shown in FIG. 5 is also structured by a conductive terminal plate or so and includes a terminal body 152a and a protrusion plate part 152b formed by bending a sheet of conductive plate-like member of a metal plate or so. The terminal body 152a includes an outer-end-surface contact portion 152a1 attached to the other terminal attachment surface 24c1 formed on the outer end surface 24c of the flange 24 shown in FIG. 2 using adhesive or so. In addition, the terminal body 152a includes a mounting-side contact portion 152a2 with a rectangular plate shape formed by bending from the lower end of the outer-end-surface contact portion 152a1 in the Z-axis direction to the X-axis direction.

The outer-end-surface contact portion 152a1 of the terminal body 152a shown in FIG. 5 is fixed to the terminal attachment surface 24c1 of the flange 24 shown in FIG. 2 using adhesive or so. The mounting-side contact portion 152a2 shown in FIG. 5 is contacted with the mounting-side core surface 24a shown in FIG. 2 with a predetermined space (or no space). The outer surface of the mounting-side contact portion 152a2 shown in FIG. 5 and located opposite to the surface contacted with the mounting-side core surface 24a shown in FIG. 2 is a sub-mounting surface 152a3. The role of the sub-mounting surface 152a3 is similar to that of the sub-mounting surface 151a3.

A lateral contact portion 152a4 contacted with a lower part of the lateral surface 24e of the flange 24 shown in FIG. 2 (see FIG. 5) is formed integrally with an outer end of the outer-end-surface contact portion 152a1 of the terminal body 152a in the Y-axis direction shown in FIG. 5. As shown in FIG. 5, the protrusion plate part 152b protruding downward in the Z-axis direction from the lateral surface 24e of the flange 24 shown in FIG. 2 is formed integrally with the terminal body 152a at a lower part of the lateral contact portion 152a4 in the Z-axis direction.

The protrusion plate part 152b includes a first base part 152e being flush with the lateral contact portion 152a4 of the terminal body 152a and extending downward in the Z-axis direction, a second base part 152c formed integrally and bending inward in the Y-axis direction from the lower end of the first base part 152e in the Z-axis direction, and a tip bending part 152d bending in turn back manner from the tip of the second base part 152c.

In the present embodiment, the tip bending part 152d bends outward in the Y-axis direction and turns back at the

11

tip of the second base part **152c**, the outer surface of the second base part **152c** located opposite to the tip bending part **152d** is a main mounting surface **152c1**, and the inner surface of the second base part **152c**, where the tip bending part **152d** is located, is a connection surface (wire connection surface) **152c2**. As shown in FIG. 4A, a lead end **42a** (one lead end) of the second wire **42** (the other wire) constituting the coil unit **40** is sandwiched and caulked by the connection surface **152c2** of the second base part **152c** and the tip bending part **152d**. After the caulking, the terminal **152** and the lead end **42a** of the wire **42** may be connected by soldering, laser welding, etc.

In the present embodiment, the main mounting surface **152c1** of the second terminal **152** protrudes downward in the Z-axis direction from the sub-mounting surface **152a3** by a predetermined distance **Z2**. In the present embodiment, the main mounting surface **152c1** is mainly connected to a circuit pattern of an external circuit board (not shown), but the sub-mounting surface **151a3** may also be connected to the circuit pattern at the same time. The connection to the circuit pattern of the external circuit board is carried out in any manner, such as solder connection.

The coil device **110** according to the present embodiment also demonstrates effects similar to those of the coil device **10** according to First Embodiment. In particular, in the coil device **110**, the second base part **151c** (**152c**), where the main mounting surface **151c1** (**152c1**) of the terminal **151** (**152**) is formed, and the lateral contact portion **151a4** (**152a4**) are connected integrally by the first base part **151e** (**152e**) (leaf spring-like support). Thus, even if an external circuit board (not shown) connected to the main mounting surface **151c1** (**152c1**) bends or vibrates due to external force, thermal deformation, or the like, the deformation of the first base part **151e** (**152e**) absorbs the deformation (force) or the vibration and can effectively protect the coil device **110**.

Third Embodiment

A coil device according to Third Embodiment of the present invention is different from the coil device **110** according to Second Embodiment only in the following structure and demonstrates effects similar to those of Second Embodiment. The overlapping matters with Second Embodiment are not explained. In the figures, common components with First and Second Embodiments are given common references.

In a coil device **110a** according to the present embodiment, as shown in FIG. 4B, a first terminal **151** and a second terminal **152** shown in FIG. 4A are respectively replaced with a first terminal **151a** and a second terminal **152a**.

The first terminal **151a** shown in FIG. 4B is structured by a conductive terminal plate or so and includes a terminal body **151a** and a protrusion plate part **151b** formed by bending a sheet of conductive plate-like member of a metal plate or so. The terminal body **151a** includes the outer-end-surface contact portion **151a1** attached to one terminal attachment surface formed on the outer end surface **24c** of the flange **24** shown in FIG. 2 using adhesive or so. In addition, the terminal body **151a** includes a mounting-side contact portion **151a2** with a rectangular plate shape formed by bending from the lower end of the outer-end-surface contact portion **151a1** in the Z-axis direction to the X-axis direction.

In the present embodiment, the lateral contact portion **151a4** shown in FIG. 5 is not formed, and as shown in FIG. 4B, the protrusion plate part **151b** protruding downward in

12

the Z-axis direction from an outer part of the outer-end-surface contact portion **151a1** in the Y-axis direction is formed integrally with the terminal body **151a**.

The protrusion plate part **151b** includes a first base part **151e** being flush with the outer-end-surface contact portion **151a1** of the terminal body **151a** and extending downward in the Z-axis direction, a second base part **151c** formed integrally and bending inward in the X-axis direction from the lower end of the first base part **151e** in the Z-axis direction, and a tip bending part **151d** bending in turn back manner from the tip of the second base part **151c**.

In the present embodiment, the tip bending part **151d** bends outward in the X-axis direction and turns back at the tip of the second base part **151c**, the outer surface of the second base part **151c** located opposite to the tip bending part **151d** is a main mounting surface **151c1**, and the inner surface of the second base part **151c**, where the tip bending part **151d** is located, is a connection surface (wire connection surface) **151c2**. As shown in FIG. 4B, a lead end **41a** (one lead end) of the first wire **41** (one wire) constituting the coil unit **40** is sandwiched and caulked by the connection surface **151c2** of the second base part **151c** and the tip bending part **151d**. After the caulking, the terminal **151** and the lead end **41a** of the wire **41** may be connected by soldering, laser welding, etc.

As with the first terminal **151a**, the second terminal **152a** shown in FIG. 4B is also structured by a conductive terminal plate or so and includes a terminal body **152a** and a protrusion plate part **152b** formed by bending a sheet of conductive plate-like member of a metal plate or so. The second terminal **152a** is structured in line-symmetric manner to the first terminal **151a** based on the Z-axis and the X-axis. That is, the terminal body **152a**, the outer-end-surface contact portion **152a1**, the mounting-side contact portion **152a2**, the sub-mounting surface **152a3**, the protrusion plate part **152b**, the second base part **152c**, the main mounting surface **152c1**, the connection surface **152c2**, and the tip bending part **152d** of the first terminal **151a** correspond with the terminal body **151a**, the outer-end-surface contact portion **151a1**, the mounting-side contact portion **151a2**, the sub-mounting surface **151a3**, the protrusion plate part **151b**, the second base part **151c**, the main mounting surface **151c1**, the connection surface **151c2**, and the tip bending part **151d** of the second terminal **152a**, respectively. These overlapping components are not explained.

The coil device **110a** according to the present embodiment also demonstrates effects similar to those of the coil device **110** according to Second Embodiment.

50 Fourth Embodiment

A coil device according to Fourth Embodiment of the present invention is different from the coil device according to First, Second, or Third Embodiment mentioned above only in the following structure and demonstrates effects similar to those of First, Second, or Third Embodiment. The overlapping matters with First, Second, or Third Embodiment are not explained. In the figures, common components with First to Third Embodiments are given common references.

As shown in FIG. 6A, a first terminal **251** used for the coil device according to the present embodiment is a modified example of the first terminal **51** shown in FIG. 3 and is structured as below.

The first terminal **251** is structured by a conductive terminal plate or so and includes a terminal body **251a** and a protrusion plate part **251b** formed by bending a sheet of

conductive plate-like member of a metal plate or so. The terminal body 251a includes an outer-end-surface contact portion 251a1 with a substantially L shape attached to one terminal attachment surface 24c1 formed on the outer end surface 24c of the flange 24 shown in FIG. 2 using adhesive or so. In addition, the terminal body 251a includes a mounting-side contact portion 251a2 with a rectangular plate shape formed by bending from the lower end of the outer-end-surface contact portion 251a1 in the Z-axis direction to the X-axis direction.

The outer-end-surface contact portion 251a1 of the terminal body 251a shown in FIG. 6A is fixed to the terminal attachment surface 24c1 of the flange 24 shown in FIG. 2 using adhesive or so. The mounting-side contact portion 251a2 shown in FIG. 6A is contacted with the mounting-side core surface 24a shown in FIG. 2 with a predetermined space (or no space). The outer surface of the mounting-side contact portion 251a2 located opposite to the surface contacted with the mounting-side core surface 24a shown in FIG. 2 is a sub-mounting surface 251a3. The role of the sub-mounting surface 251a3 is similar to that of the sub-mounting surface 51a3 shown in FIG. 3.

The protrusion plate part 251b shown in FIG. 6A and protruding outward in the Y-axis direction from the mounting-side core surface 24a of the flange 24 at the lower end of the flange 24 shown in FIG. 2 is formed integrally with the mounting-side contact portion 251a2 of the terminal body 251a shown in FIG. 6A. The protrusion plate part 251b includes a base part 251c being flush with the mounting-side contact portion 251a2 of the terminal body 251a and extending outward in the Y-axis direction and a tip bending part 251d bending downward in turn back manner in the Z-axis direction from the tip of the base part 251c.

In the present embodiment, the tip bending part 251d bends downward in the Z-axis direction and turns back at the tip of the base part 251c, the outer surface of the tip bending part 251d located opposite to the base part 251c is a main mounting surface 251d1, and the inner surface of the tip bending part 251d, where the base part 251c is located, is a connection surface (wire connection surface) 251d2. A lead end 41a (one lead end) of a first wire 41 (one wire) constituting the coil unit 40 is sandwiched and caulked by the connection surface 251d2 of the tip bending part 251d and the base part 251c. After the caulking, the terminal 251 and the lead end 41a of the wire 41 may be connected by soldering, laser welding, etc.

In the present embodiment, the main mounting surface 251d1 of the first terminal 251 protrudes downward in the Z-axis direction from the sub-mounting surface 251a3, and the main mounting surface 251d1 is mainly connected to a circuit pattern of an external circuit board (not shown), but the sub-mounting surface 251a3 may also be connected to the circuit pattern at the same time. The connection to the circuit pattern of the external circuit board is carried out in any manner, such as solder connection.

In the present embodiment, the connection surface 251d2 (wire connection surface) and the main mounting surface 251d1 are formed on the front surface and the rear surface of the tip bending part 251d of the first terminal 251, respectively.

Incidentally, the second terminal used for the coil device according to the present embodiment is symmetrical to the first terminal 251 in terms of shape and has the same structure excluding the symmetry.

A first terminal 251a shown in FIG. 6B is a modified example of the first terminal 251 according to the present embodiment. In the first terminal 251a according to the

present embodiment, a step 253 is integrally formed between the mounting-side contact portion 251a2 and the base part 251c, and the upper surface of the base part 251c is higher than that of the mounting-side contact portion 251a2 in the Z-axis direction. As a result, the main mounting surface 251d1 of the tip bending part 251d is substantially flush with the sub-mounting surface 251a3.

FIG. 6C illustrates another modified example of the first terminal 51 shown in FIG. 3. In this modified example, the tip bending part 51d shown in FIG. 3 is not formed on the protrusion plate part 51b, and the lead end 41a of the first wire is directly connected to the connecting surface 51c2 of the base part 51c by laser welding, soldering, heat welding, or the like.

Incidentally, the present invention is not limited to the above-mentioned embodiments and can variously be modified within the scope of the present invention.

In the above-mentioned embodiments, for example, the first flange 24 and the second flange 26 have the same structure, but may have different structures. The width of the notches 24c3 in the Y-axis direction formed at the lower ends of the flange 24 (26) of the drum core 20 shown in FIG. 2 on both sides in the Y-axis direction may be large. For example, the notches 24c3 on both sides may be connected to each other in the Y-axis direction. In this case, the mounting-side core surface 24a (26a) of the flange 24 (26) of the drum core 20 shown in FIG. 2 is flush with the bottom surface of the notches 24c3 (26c3).

In the above-mentioned embodiments, the plurality of wires (the first wire 41 and the second wire 42) is wound around the winding core 22 of the drum core 20. In the present invention, however, a single wire (e.g., only the first wire 41) may be wound around the winding core 22 of the drum core 20. In this case, the lead ends 41a and 41b on both ends of the first wire 41 are connected to any of the first terminal 51, 51a, 151, 151a, 251, or 251a attached to the flanges 24 and 26. The lead end 41a (one lead end) of the first wire 41 may be connected to the first terminal attached to the flange 24, and the lead end 41b (the other lead end) may be connected to the second terminal attached to the flange 26.

In the above-mentioned embodiments, the first terminal and the second terminal attached to each of the flanges 24 and 26 are insulated from each other, but when a single wire (e.g., only the first wire 41) is wound around the winding core 22 of the drum core 20, the first terminal and the second terminal attached to the same flange 24 (26) may electrically be connected to each other. That is, the first terminal and the second terminal attached to the same flange 24 (26) may be formed integrally from a sheet of metal plate.

 What is claimed is:
 1. A coil device comprising:
 a winding core made of a magnetic material;
 a flange integrated with the winding core;
 a wire wound around the winding core; and
 a terminal fitting attached to a part of an outer surface of
 the flange, wherein
 the terminal fitting includes:
 a contact part contacted with the outer surface of the
 flange; and
 a protrusion plate part integral with the contact part and
 protruding away from the flange, and
 the protrusion plate part includes:

16

a wire connection surface to which a lead end of the
 wire is connected; and
 a main mounting surface opposite to the wire connection
 surface and configured to physically contact a
 surface of an external circuit.
 2. The coil device according to claim 1, wherein
 the protrusion plate part includes:
 a base part continuing to the contact part and protruding
 from the flange, and
 a tip bending part bending in turn back manner at a tip
 of the base part; and
 the lead end of the wire is sandwiched between the tip
 bending part and the base part.
 3. The coil device according to claim 2,
 wherein the wire connection surface or the main mounting
 surface is on a front surface or a rear surface of the tip
 bending part.
 4. The coil device according to claim 2, wherein the wire
 connection surface is on an inner surface of the base part,
 and the main mounting surface is on an outer surface of the
 base part.
 5. The coil device according to claim 1, wherein a
 sub-mounting surface is on a part of an outer surface of the
 contact part, the sub-mounting surface being flush with the
 main mounting surface or being on an inner side of the main
 mounting surface.
 6. The coil device according to claim 1, wherein a gap
 distance between the protrusion plate part and the flange in
 a perpendicular direction to the main mounting surface is
 twice or larger than a thickness of the protrusion plate part
 at a location where the lead end of the wire is connected to
 the protrusion plate part.
 7. The coil device according to claim 1, wherein a
 plate-like member is bonded on the outer surface of the
 flange opposite to the main mounting surface.
 8. A coil device comprising:
 a winding core made of a magnetic material;
 a flange integrated with the winding core;
 a wire wound around the winding core; and
 a terminal fitting attached to a part of an outer surface of
 the flange, wherein
 the terminal fitting includes:
 a contact part contacted with the outer surface of the
 flange; and
 a protrusion plate part integral with the contact part and
 protruding away from the flange,
 the protrusion plate part includes:
 a wire connection surface to which a lead end of the
 wire is connected; and
 a main mounting surface opposite to the wire connection
 surface and being connectable to an external
 circuit, and
 a sub-mounting surface is on a part of an outer surface of
 the contact part, the sub-mounting surface being flush
 with the main mounting surface or being on an inner
 side of the main mounting surface.
